Primary Examiner — Kendra Leslie Hamilton*Assistant Examiner* — Amanda Christensen(74) *Attorney, Agent, or Firm* — Greer, Burns & Crain, Ltd(57) **CLAIM**

The ornamental design for a charging stand for hair clipper, as shown and described.

DESCRIPTION

FIG. 1 is a top, front, right side perspective view of a charging stand for hair clipper;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the charging stand for hair clipper that form no part of the claimed design.
